(57) CLAIM

I claim the ornamental design for a ring with star of David,
as shown.

DESCRIPTION

FIG. 1 is a perspective view of a ring embodying my design;
FIG. 2 is a front view thereof, it being understood that the rear is substantially similar;

FIG. 3 is a top plan view thereof;

FIG. 4 is a bottom plan view thereof; and,

FIG. 5 is a right side elevation view thereof, it being understood that the left side elevation view is substantially similar.
